ORCHARD HEATER COMPANY, OF WHEELING, WEST VIRGINIA, A CORPORATION
OF WEST VIRGINIA.

DRAFT-REGULATOR FOR ORCHARD-HEATERS.

1,134,764.

Specification of Letters Patent.

Patented Apr. 6, 1915.

Application filed April 10, 1914. Serial No. 830,941.

To all whom it may concern:

Be it known that I, WILLIAM C. SCHEU, a citizen of the United States of America, and resident of Grand Junction, county of 5 Mesa, and State of Colorado, have invented certain new and useful Improvements in Draft-Regulators for Orchard-Heaters, of which the following is a specification.

This invention relates broadly to orchard 10 heaters, and specifically to draft appliances for such heaters.

The primary object of the invention is to provide, in connection with an orchard heater wherein liquid fuel is used, a simple 15 and efficient device whereby the admission of a draft or drafts of air to the surface of the liquid fuel may be controlled for regulating the rapidity of combustion and, consequently, for regulating the amount of heat 20 generated.

A further object is to provide means for continuously introducing air to the fuel within the fuel container associated with means whereby a strong blast of air may be introduced upon the surface of said fuel when the latter has burned down to a point where it has become less volatile and combustion has become increasingly difficult. 25 And a still further object is to provide a draft regulator for orchard heaters which, when once adjusted to supply air for producing either a medium or strong fire, is automatic to the extent that no further adjustment is required to accomplish the 30 consumption of all the fuel in the container with a substantially steady generation of heat.

With these and other objects in view, the invention resides in the features of construction, arrangement of parts and combinations of elements which will hereinafter be fully described, reference being had to the accompanying drawings, forming a part of this specification, in which—

45 Figure 1 is a top plan view of an orchard heater embodying my invention; Fig. 2 is a vertical section on the line 2—2, Fig. 1; Fig. 3 is a similar section on line 3—3, Fig. 1, showing a modified form of blast tube; 50 Fig. 4 is an enlarged detail section on the line 4—4, Fig. 2, showing the preferred form of blast tube; Fig. 5 is an enlarged top plan view of the draft regulator, showing the ro-

tary disk in a position permitting the introduction of a strong blast of air through 55 the blast tube; and Fig. 6 is a similar view showing the draft to the tubes completely cut off.

Referring to said drawings, in which like designating characters distinguish like parts throughout the several views—1 indicates the oil container or receptacle of an ordinary type of orchard heater, and 2 a removable cover therefor, said cover being of frusto-conical form and having a central 65 opening or flue inclosed by the lower end of a stack 3. At a point laterally of the stack, the cover is upwardly dished to form a flat circular platform 4. Rigidly attached to said cover, by any suitable means, preferably by spot-welding, so as to embrace said platform 4 is the lateral base-flange 5 of a circular upwardly-dished plate 6 having a flat surface. Projected through and suspended from said plate at points lateral 75 with respect to its center are two tubes 7 and 8, the former being a draft tube and the latter a blast tube. Said tubes are but slightly separated, as shown, and have their axes located at points equidistant from the center of said plate. Said tubes depend within the container 1, being projected through suitable openings 9 and 10 provided therefor in the platform 4 at points in substantial vertical alinement with the openings 80 in which they are fitted in plate 6.

Pivoted centrally upon and resting closely on said plate 6 is a rotary disk 11 having a large circular aperture or opening 12 appropriately located therein and adapted to be brought into direct registration with either of the tubes 7 or 8. Also located in said disk are two relatively smaller circular apertures 13 and 14 the radial distance of whose centers from the pivot 15 is the same 95 as that of the axes of the tubes 7 and 8 from said pivot. Further, the openings 12 and 13 have their centers separated a distance substantially equal to that separating the axes of said tubes 7 and 8; and the openings 13 and 14 have their centers separated a like distance: so that either the first mentioned two thereof or the last mentioned two thereof may simultaneously register with the tubes 7 and 8. Thus, as will be obvious, 100 when aperture 12 registers with draft tube

7, aperture 13 also registers with blast tube 8; when aperture 13 registers with draft tube 7, aperture 14 also registers with blast tube 8; and when aperture 12 registers with 5 blast tube 8, draft tube 7 remains wholly closed against the admission of air.

Substantially V-shaped lugs 16 and 17 are struck up at appropriately located points and stand in substantially vertical positions, 10 said lugs constituting stops against which the upright arm of a finger-piece 18 carried by said disk abuts for limiting the extent of rotation of the disk in either direction, as shown in Figs. 5 and 6.

15 The draft tube 7 is provided with a longitudinal slot in one side thereof. While said slot may be of any desired length, it preferably extends from a point in close proximity to the platform 4 to a point close to the 20 lower end of the tube, as shown, thus permitting the air admitted through its upper end to be freely discharged over the surface of the liquid fuel in the container irrespective of the depth of said fuel. On the other 25 hand, tube 8 is designed as a blast-tube for directing a strong blast of air at a single point on the surface of the fuel when the latter has been consumed down to a point where the lower end of the tube is exposed, 30 thus producing combustion of substantially a blow-torch character which results in the less volatile portion of the fuel being completely consumed so as to leave no residuum in the container. Said tube is therefore 35 preferably made solid and imperforate, or substantially so, from end to end, as shown in Fig. 4, although a plurality of small perforations may, if desired, be provided therein, as shown in tube 8^a in Fig. 3.

40 In practice, when the container 1 is full and but a medium fire is required for burning continuously over a period of several hours' duration, the disk 11 is rotated to a point wherein small aperture 13 registers 45 with draft tube 7. When it is desired to produce a strong fire which will require no adjustment of the regulator during a period of several hours' duration, the rotation of said disk is continued until the large aperture 12 50 registers with draft tube 7. In the first-mentioned position of the disk the small aperture 14 also registers with blast tube 8, and in the last mentioned position the small aperture 13 also registers with said blast tube 8; but this registration with tube 8 has 55 no effect upon combustion until the fuel level has receded to a point where the lower end of said blast tube 8 is uncovered, provided tube 8 is imperforate, as shown in Fig. 4; or, if said tube is perforated to some extent, as shown in Fig. 3 wherein is illustrated a modified form of said tube, a small additional volume of air will of course be admitted to the container through the perforations. A sufficient volume of air is 60

65 introduced through draft tube 7 alone for producing efficient combustion of the lighter, more volatile portion of the fuel; and when combustion becomes more difficult, as when the lighter surface oil has been consumed, 70 the lower end of blast tube 8 is uncovered, admitting a blast of air therethrough which facilitates combustion to the extent that all of the fuel will be consumed. When 75 it is desired that a strong blast of air be introduced upon the surface of the fuel, as when the fuel is of low grade and it has burned down to a point where it is consumed with difficulty, the disk may be rotated to a point where aperture 12 registers with blast 80 tube 8.

85 As is obvious, the manner of adjustment of the disk will necessarily be determined to a great extent by the character and quality of the liquid fuel employed and by the amount of heat which it is desired to generate, variations in adjustment being required for different grades of fuel, for the same fuel at different levels within the container, and for regulating the rapidity of 90 combustion for producing a desired intensity of heat. It will however be noted that, the disk having been adjusted with two of its apertures in registering relation to the tubes 95 7 and 8, the regulation of combustion is thereafter accomplished automatically, the rate of combustion being substantially constant until the more volatile portion of the fuel has been consumed, at or about which time the lower end of tube 8 is uncovered, admitting therethrough additional air which imparts renewed vigor or impetus to the combustion.

100 Having thus described my invention, what I claim as new, and desire to secure by Letters Patent, is—

1. In an orchard heater, the combination with a fuel container, of a cover for said container, a plurality of tubes projected through said cover and depending within said container, and a disk mounted to rotate over said tubes, said disk having therein a plurality of apertures which are so located that one or more of said tubes may be opened for the admission of air therethrough, one of said apertures differing in size from the others.

110 2. In an orchard heater, the combination with a fuel container, of a cover for said container, two tubes projected through said cover and depending within said container, a disk mounted to rotate over said tubes, said disk having an aperture therein which is adapted upon rotation of said disk to assume registering relation with either of said tubes, and said disk having two relatively smaller apertures therein which are spaced from the first mentioned aperture and from each other so that either the large and a small aperture may simultaneously register 115 120 125 130

with the two tubes or the two smaller apertures may simultaneously register with said tubes.

3. In an orchard heater, the combination 5 with a fuel container, of a cover for said container, a draft tube and a blast tube projected through said cover and depending within said container, a disk mounted to rotate over said tubes, said disk having a large 10 aperture and two smaller apertures therein, said apertures having their centers disposed at points substantially equidistant from the center of said disk, and adjacent apertures having their centers separated from each 15 other a distance substantially equal to that between the axes of said tubes.

4. In an orchard heater, the combination with a fuel container, of a cover for said container, an upwardly dished flat platform 20 formed on said cover, a draft tube and a blast tube projected through said platform and depending within said container, a disk mounted to rotate over said tubes, said disk having a large aperture and two smaller 25 apertures therein, each of said apertures being adapted to register with each of said tubes at points in the rotation of said disk, adjacent apertures having their centers separated a distance substantially corresponding to that separating the axes of said 30 tubes, so that in one position of said disk both of the said tubes are closed, in another position the blast tube is opened to its full capacity while the draft tube is maintained 35 closed, in another position the draft tube is opened to its full capacity and the blast tube is opened to a part only of its capacity, and in another position both tubes are opened to a part only of their respective capacities.

40 5. In an orchard heater, the combination with a fuel container of a cover for said container, an upwardly-dished flat platform formed in said cover, a circular plate mounted in embracing relation to said platform, a draft tube and a blast tube projected through said plate and said platform and suspended from the former within said container, a disk mounted to rotate over said tubes, said disk having a large aperture and 45 two smaller apertures therein, said apertures having their centers located at points substantially equidistant from the center of

said disk, and adjacent apertures having their centers separated from each other a distance substantially corresponding to that 55 separating the axes of said tubes.

6. In an orchard heater, the combination with an oil container, of automatic draft-regulating means comprising a draft tube and a blast tube suspended within the container from said cover, said draft tube being adapted to continuously conduct air to the surface of the oil irrespective of the depth of the latter, and said blast tube being adapted to conduct air to the surface of the oil in large volume after the latter has 60 burned to a level where the lower end thereof is uncovered, and a rotatable disk mounted over the upper ends of said tubes and having openings therein adapted in one position of the disk to admit air to both of 65 said tubes.

7. In an orchard heater, the combination with an oil container, of automatic draft-regulating means comprising a draft tube 75 and a blast tube suspended within the container from said cover, said draft tube being adapted to continuously conduct air to the surface of the oil irrespective of the depth of the latter, and said blast tube being 80 adapted to conduct air in large volume to the surface of the oil after the latter has burned to a level where the lower end thereof is uncovered, and a rotatable disk mounted over the upper ends of the said tubes and 85 having a series of openings of varied sizes therein, said tubes having their axes located laterally with respect to and equidistant from the axis of said disk, said openings being spaced from the axis of the disk a distance corresponding to the distance of the tubes from said axis and also being separated a distance corresponding to the distance between said tubes, so that both tubes 90 may be opened to the admission of air and that either a large or medium volume of air 95 may be admitted through the draft tube.

In testimony whereof, I affix my signature in presence of two subscribing witnesses.
